COMBINATION LOCK

Filed Nov. 29, 1946

2 Sheets-Sheet 2

FIG. 5.

FIG. 6.

FIG. 7.

Morris Relson
ATTORNEY

whose sides 34 are bent up at right angles to form bearing surfaces sliding against the underside of base plate 21 and thereby guiding the latch 19 for motion parallel to base plate 21. Slider 33 also has an opening 36 with parallel sides which bear against the edges of post 24 and thereby restrain slider 33 for motion only in a straight line toward and away from the hasp loop 18.

Slider 33 also has a circular opening 37 which rotatably receives the main body 39 and a tumbler pin 38. In this way tumbler pin 38 and slider 33 may move rectilinearly together, while tumbler pin 38 may rotate with respect to slider 33. Tumbler pin 38 also passes through an opening 41 in base plate 21, which is just wide enough to receive pin 38 but long enough to permit translation of the tumbler pin and slider unit. It will be understood that when tumbler pin 38 is at the right-most end of opening 41, latch 19 engages hasp loop 18, while motion of pin 38 to the left also moves slider 33 and latch 19 to release hasp loop 18, whereby the hasp arm 13 is permitted to swing back, unlocking the luggage device. Normally slider 33 and latch 19 are retained in the right-most (closed) position by a tension latch spring 42 looped at one end around a projection 43 and at the other end around a projection 44 struck out of the bottom of cover 26.

As will be apparent from the above description, the present lock is of the type wherein the tumbler pin 38 is kept from translational movement except in one predetermined angular position, so that the latch 19 can release hasp arm 13 only when tumbler pin 38 is properly adjusted to its predetermined position. To indicate this proper position, a combination disc 48 is fixed to the end 49 of tumbler pin 38 passing through base plate 21. Disc 48 is provided with a finger knob 51 and indicia 52 which cooperate with similar indicia 53 formed on base plate 21, so that a plurality of different positions of tumbler pin 38 are denoted by the various alignments of one of the indicia 52 with one of indicia 53, in the manner described and claimed in my above-mentioned copending application.

To release hasp arm 13, tumbler pin 38 has an opening 46 formed therein (as by boring) and extending substantially along a diameter of the pin. This opening 46 cooperates with a key 47 to permit translation of tumbler pin 38 and slider 33 only when key 47 is in register with opening 46, and to prevent such translation when out of register.

It will be seen that lock 11 might be opened by tactile manipulation and without knowledge of the proper combination, by merely feeling when key 47 slips into opening 46, unless special provision is made to prevent such unauthorized tampering. Such an anti-tampering means forms an important and novel feature of the present invention.

For this purpose, key 47 is made as an integral part of a locker plate 54 which has a large central aperture 56 adapted to surround tumbler pin 38 without interfering with its motion, and also having a second aperture 57 freely surrounding post 24. Locker plate 54 is kept between base plate 21 and slider 33, the tumbler pin 38 and combination disc 48 serving also as a fastening device to retain the former elements together. However, the sides 34 of slider 33 space the slider 33 sufficiently from base plate 21 to permit locker plate 54 to have a limited vertical movement, for reasons which will appear below.

Also struck out from base plate 21 are a pair

of projections 58 having respective ledges or shoulders 59 upon which the left end of locker plate 54 is adapted to be seated, as shown in Figs. 3, 4, 5 and 6. Locker plate 54 is normally urged upward by the action of a leaf spring 61 which is fixedly held around the small end 29 of post 24, between post 24 and cover 26, when the cover 26 is put in place. Spring 61 has a portion 62 bearing against the left end of locker plate 54, the spring 61 being cut away at 63 to clear the slider 33. A further portion 64 of spring 61 bears against the enlarged head 66 of tumbler pin 38 and urges it upwardly also, thereby keeping combination disc 48 above base plate 21 and minimizing friction therebetween. Opening 57 in locker plate 54 is made sufficiently wide so that locker plate 54 can freely move from a position in which it is seated upon ledges 59 of base plate projections 58, as shown in Figs. 3 to 6, to a position in which the locker plate 54 is off the ledges 59, as shown in Fig. 2. Since spring 61 constantly urges locker plate 54 upwards, it will be seen that the locker plate 54 can be moved from the seated position as in Figs. 3 to 6 to the unseated position as in Fig. 2 merely by being moved leftward slightly. In so doing, the left portion of locker plate 54 is moved by spring 61 to a position touching the underside of base plate 21, by pivoting around a pair of upwardly extending, integrally formed rounded ears 67 formed on locker plate 54 and which serve as fulcrums by rolling on the underside of base plate 21.

Locker plate 54 provides the anti-tampering feature mentioned above, since key 47 carried by locker plate 54 can never be in register with the tumbler opening 46 when locker plate 54 is unseated from ledges 59. This will be apparent from Fig. 2, which shows the lock in this state; thus, with locker plate 54 unseated, key 47 is displaced vertically with respect to opening 46 of tumbler pin 38 so that key 47 cannot possibly register with opening 46. In this state, any pressure on combination disc 48 in a leftward direction (as is necessary to retract latch 19 and release hasp arm 13) is blocked, since such pressure merely causes the right end 68 of locker plate 54 to abut post 24, thus stopping any movement, except for possibly a small clearance which is made too small to permit latch 19 to release hasp loop 18, and the lock remains closed. To further assure this condition, tumbler pin 38 is made tapered opposite key 47 when in the unseated position, as shown at 69. By this means, any leftward pressure causes key 47 to ride upward on taper 69 and away from opening 46, thus making certain that key 47 will not register with opening 46 even by accident.

When locker plate 54 is in the seated position and when key 47 and opening 46 are in register by setting the proper combination on indicia 52 and 53 as shown in Fig. 5, tumbler pin 38 can freely move leftward, since then opening 46 freely surrounds key 47. In this way, slider 33 is moved leftward to release hasp loop 18 from latch 19, and to permit hasp arm 13 to disengage lock 11, thereby unlocking the luggage device as desired. In this position, the apparatus may be retained "on latch," since latch spring 42 retains latch 19 normally in the closed position. Latch 19 is tapered as at 71, so that by pushing hasp arm 13 downward, latch 19 and slider 33 are forced leftward by wedge action until hasp loop 18 descends below latch 19, whereupon spring 42 snaps latch 19 back into loop 18, retaining the apparatus closed. A slight leftward pressure on combina-

tion disc 48 will serve to release hasp arm 13 to open the apparatus, when desired.

However, when the proper combination is not set, and even though locker plate 54 may be in the seated position, as shown in Fig. 3, any leftward pressure on combination disc 48, such as an unauthorized attempt to open the lock, will merely serve to unseat locker plate 54 from ledges 59, since any leftward motion of combination disc 48 and tumbler pin 38 fixed thereto is communicated to key 47 and thence to locker plate 54, to put it into the unseated position shown in Fig. 2, in which position it is impossible to open the lock at all. Thus any tampering with the apparatus immediately results in putting it into a condition where opening is impossible, whereby such unauthorized attempts to open the device are at once frustrated.

To reset the locker plate 54 to the seated position shown in Figs. 3 and 4 so as to permit opening the lock when the proper combination is set, key 47 is formed with a rounded tip as seen most clearly in Fig. 6. A resetting pin 72 is fixed to tumbler pin 38 substantially at the lower edge of the taper 69 thereof. Resetting pin 72 is preferably press-fitted into a hole drilled through tumbler pin 38 in a plane perpendicular to the axis of tumbler pin 38 but extending outwardly from tumbler 38 at a slight angle to the radius thereof. Pin 72 is spaced circumferentially from the opening 46 by a substantial angle, such as of the order of 105 degrees. In this way, by rotating combination disc 48 and tumbler pin 38, resetting pin 72 strikes the rounded tip of key 47 and forces key 47 and the left end of locker plate 54 downward to clear ledges 59. The cross-bar 73 of locker plate 54 is located so that when locker plate 54 is in the position shown in Fig. 2, spring 42 is stretched slightly and is under tension. Therefore, when key 47 has been depressed by resetting pin 72 until locker plate 54 clears ledges 59, the spring 42 moves the slider 33 tumbler 38 and locker plate 54 to the right to assure seating of locker plate 54 on ledges 59, and to retain the seated condition until leftward pressure is applied to tumbler 38, as discussed above.

By having pin 72 angularly displaced from the opening 46 by a substantial angle, any unauthorized person tampering with the lock (and not knowing its combination) would have to give the combination disc 48 practically a complete turn each time he tried to release latch 19. In this way, unless the exact proper combination is known, it is rendered very difficult to open the lock, mere tactile manipulation being frustrated by the action of locker plate 54.

From the above description the method of operating the present lock will be apparent. The user each time should preliminarily turn combination disc 48 through at least one complete revolution, so that resetting pin 72 will insure that locker plate 54 is seated on ledges 59. Then the disc 48 is rotated to the known combination, and thereafter a leftward movement of disc 48 will retract latch 19 and release hasp 13. So long as disc 48 is kept set at the proper combination, the lock will remain "on latch" as already described.

It will be clear from the above that the lock of the present invention is extremely easy to fabricate in large quantities, since practically all the parts are merely stamped, turned or drilled, all of which are very simple manufacturing steps. Thus a simple and inexpensive lock is provided.

while still providing very effective anti-tampering features.

Since it will be apparent that many variations of the present invention are possible, the foregoing description is intended to be illustrative only, and is not to be construed as limiting in any way the scope of the present invention, which is defined in the following claims.

I claim as my invention:

- 10 1. A combination lock comprising a base plate, a slider member mounted for sliding motion relative to said base plate and having a hasp-retaining latch member thereon, a cylindrical tumbler member rotatably carried by said slider member for conjoint sliding therewith but rotatable with respect thereto, said tumbler member having an opening in the side thereof extending in a plane perpendicular to the axis of said tumbler member, a locker member mounted between said slider member and said base plate and surrounding said tumbler member, said locker member having a key thereon adapted substantially to prevent sliding movement of said slider and tumbler members except when said key and opening are in register, whereupon said movement is permitted, said locker plate having a fulcrum bearing on said base plate and adapting it for pivotal movement relative to said base plate, said base plate having a pair of projections normally maintaining said locker plate spaced from said base plate and maintaining said key in the plane of said opening, said locker plate also having means cooperating with said tumbler member to unseat said locker plate from said projections in response to movement of said tumbler member in a direction to retract said latch when said key and opening are not in register, whereby said key is moved from said opening plane so as to prevent said registering no matter what position said tumbler member assumes, and means carried by said tumbler member and cooperating with said key to restore said locker plate to a seated position upon said projections in response to rotation of said tumbler member through a predetermined angle.
- 20 2. A combination lock as in claim 1 wherein said key is formed as a projection on said locker plate curving toward said base plate and having a rounded tip, said tumbler member having a tapered portion opposite said tip when said locker plate is in the unseated position and converging away from said opening, whereby said tip is maintained away from said opening, said locker-plate-restoring means including a pin projecting from the side of said tumbler member and adapted to force said key tip away from said tapered portion by cam action upon rotation of said tumbler member.
- 30 3. A combination lock comprising a base plate, a slider having a hasp-retaining latch and mounted for sliding movement relative to said base plate, a tumbler pin rotatably connected to said slider for conjoint sliding but independent rotation, said tumbler pin passing through said base plate for both rotary and translational movement with respect thereto, said tumbler pin having an opening therein, a key normally mounted to register with said opening upon rotational adjustment of said tumbler pin to a predetermined position and adapted substantially to prevent translational movement of said tumbler pin and slider except when said key and said opening are in register, and means responsive to attempted translation of said tumbler pin during lack of register between said key and said opening for moving said key from its normal position

to a new position rendering such registering impossible.

4. A combination lock as in claim 3 further including means responsive to rotation of said tumbler pin through a predetermined angle for restoring said key to its normal position, whereby said slider may be translated upon adjustment of said tumbler pin to said predetermined position at which said key and opening are in register.

5. In a combination lock having a rotatably and translationally adjustable tumbler member, said member having an opening therein, a latch member connected to said member for conjoint translational movement only, and means including a key member for preventing translational movement of said tumbler member except when said key member and said opening are in register, the improvement comprising means responsive to attempted translation of said tumbler member during lack of register between said key member and said opening for relocating said key member to a position where said registering is impossible for all positions of said tumbler member.

6. A combination lock comprising a slider member mounted for rectilinear movement and having a latch member thereon, a tumbler member rotatably connected to said slider member for conjoint translation therewith, means normally preventing said translation and consequent retraction of said latch member except in a predetermined rotary position of said tumbler member, and means responsive to attempted translation of said tumbler member when not in said predetermined position for rendering said first-named means ineffective to permit such translation even when said tumbler member is in said predetermined position.

7. A combination lock as in claim 6 wherein said tumbler member has an opening in a given plane, said first-named means comprising a key having a normal position in said plane in which it is adapted to prevent said translation except for said predetermined rotary position of said tumbler member in which said key and opening are in register, and wherein said last-named means comprises means responsive to attempted translation of said tumbler member when said key and opening are out of register, for moving said key away from said given plane, whereby said key and opening cannot be in register even at said tumbler member's predetermined position.

8. In a combination lock having a latch and a combined rotary tumbler and latch-releasing member, the combination comprising means normally preventing latch-releasing operation of said member except in a predetermined rotary position of said member, and means responsive to attempted latch-releasing operation of said member when not in said predetermined position for rendering said first-named means ineffective to permit such operation even in said predetermined position of said member.
